UNITED STATES PATENT OFFICE.

HENRI DANTIN, OF BORDEAUX, FRANCE.

DOUBLE-ACTING PUMP.

Application filed August 26, 1921. Serial No. 495,568.

To all whom it may concern:

Be it known that I, HENRI DANTIN, citizen of the Republic of France, and resident of Bordeaux, France, (post-office address 5 358 cours de Coulouse), have invented new and useful Improvements in Double-Acting Pumps (for which I have filed application in France on the 21st of August, 1920, No. 522,771), of which the following is a specification.

My invention relates to a double acting pump with one or several cylinders, comprising a single X-shaped valve piece and a single winged setting bolt so as to permit 15 instantaneous dismantling.

In order to make my invention more clearly understood, I have appended hereto drawings showing, as an example, an embodiment thereof.

20 In the said drawings:

Figure 1, is a longitudinal section of my pump;

Figure 2, is a side view of the same;

25 Figure 3, shows a modification of the device.

As illustrated by the figures, the device is constituted by a cylinder A within which moves a piston B, carrying a rod C. Cylinder A has on one of its ends a plate E, secured by bolts O and O' and on its other end a stuffing box plate D and a stuffing box D¹.

In the upper part of the said cylinder are provided two apertures or ports V and V¹ 35 permitting the liquid or gas to pass.

The upper part or dome K of the pump has suction J and forcing I openings and encloses a valve piece G shaped as a mobile X and secured by a winged bolt N. The 40 latter is screwed in at H and presses upon the closing plug M.

The valve piece has apertures closed by valves F, F¹, F², F³, moving upon pivots Z¹, Z², Z³, Z⁴, respectively. The pump is secured 45 on a suitable device or support by means of two lugs L¹, L², located at its lower part.

Bearing the above explanations in mind, the working of my pump is as follows:

When piston B moves from right to left 50 within cylinder A, there simultaneously occur, due to the pump being a double acting one, a suction and a forcing of liquid or gas through the suction J and forcing I openings or ports, the effect of which is to open valves F and F¹ carried by the X-shaped device. When the piston B has reached the

end of its travel and the reverse motion takes place, valves F, F² and F³ open in their turn while valves F and F¹ close and the liquid or gas is forced through port 1. The motions continuing, the the same suction and forcing phases are repeated indefinitely with the same regularity.

My pump, being of the horizontal type, can be mounted on any carriage and serve 65 for pumping any liquids; it can be used for watering, irrigating, etc.

Readily portable, its encumbrance is very small; its working is quite smooth and its delivery huge, while it can be beam,—or 70 wheel—or motor-operated.

Valves can be instantly removed by unscrewing the single winged bolt shown by Figure 2.

My pump can also be constructed with one 75 or several cylinders, while comprising a single X-shaped valve piece and a single winged bolt.

It becomes bplex, triplex or quadruplex and its delivery corresponds to the number 80 of cylinders which can be mounted twin or tandemwise.

It can also be transformed into a vacuum pump or into an air compressor, or a compressor for any gas. For this purpose the 85 valves have simply to be replaced by ground valves with guides.

Figure 3 illustrates a modification, consisting in the intercalating of a T or such like device between the forcing valves. This 90 T, as indicated by its name, is made up of three branches or arms, one of which is horizontal 1; and caught in its middle by vertical arm 2 forming the T. The vertical arm 2, longer than the horizontal one, terminates 95 at its base in a boss 3 provided with a central hole intended to house an axle 4; this boss is embedded in the jaws of a small block 5 carrying the axle, which allows the T a right and left oscillatory motion.

The T can be made of iron, cast-iron, bronze, etc. the nature of the material being selected according to the kind of liquids to be pumped.

As shown in the drawing, the T is positioned between two forcing valves facing one another, both for the double acting pump and for quadruplex or sextuplex ones.

The working of the T is as follows:

Let us suppose that, as shown in the ap- 110 pended drawing, right valve F¹ opens under the pressure of the liquid or forcing, the

valve coming into contact with the right arm of the **T** thus causes the latter to tilt. Due to this motion, the left arm of the **T** bears on the left valve, exerting on the latter 5 a pressure equal to the liquid pressure that lifts the right valve, the consequence being a prompt closure of the left valve. When it is the left valve **F** that is lifted by the forcing 10 action of the liquid, it is the right arm of the **T** which suddenly closes valve **F**¹. It will be realised therefore, that the **T** acts on the valve for the purpose of promptly returning those 15 parts to their seats. In this manner the serious drawbacks resulting from the valves floating in the liquid are done away with, consequently delivery is increased since back-flow is prevented.

Besides, the afore described arrangement allows very light valves of any shape may 20 be used without any possibility of the form adopted nor the lightness thereof injuriously interfering with the pump delivery whatever the sort of pump used.

Having now particularly described and 25 ascertained the nature of my said invention, and the manner in which the same is to be performed, what I claim is:

1. A pump of the type set forth having a 30 valve chamber, an **X** shaped frame received within and dividing said chamber into a suction and pressure compartments, a pair of normally closed valves carried by said frame adapted to be opened by the pressure of the 35 fluid delivered by said pump and means interposed between said valves adapted to be

actuated by the opening of one valve to cause the closing of the other valve.

2. A pump of the type set forth having a valve chamber, an **X** shaped frame received within and dividing said chamber into a suction and pressure compartments a pair of normally closed valves carried by 40 said frame adapted to be opened by the pressure of the fluid delivered by said pump and means interposed between said valves 45 adapted to be actuated by the opening of one valve to cause the closing of the other valve, said means pivoted to said frame intermediate the walls thereof.

3. A pump of the type set forth having a 50 valve chamber, an **X** shaped frame received within and dividing said chamber into a suction and pressure compartments, a pair of normally closed valves carried by said frame adapted to be opened by the pressure of the 55 fluid delivered by said pump and means interposed between said valves adapted to be actuated by the opening of one valve to cause the closing of the other valve, said means comprising a **T** shaped member pivoted to said frame and extending between 60 said valves.

In testimony whereof I have signed this specification in the presence of two subscribing witnesses.

HENRI DANTIN.
